UNITED STATES PATENT OFFICE.

ORRIN B. READ, OF TROY, NEW YORK.

DESIGN FOR A REIN-TERRET.

41,746.

Specification for Design.

Patented Sept. 5, 1911.

Application filed December 21, 1908. Serial No. 468,697. Term of patent 14 years.

To all whom it may concern:

Be it known that I, ORRIN B. READ, a citizen of the United States, residing at Troy, in the county of Rensselaer and State of New York, have invented a new, original, and ornamental Design for Rein-Terrets, of which the following is a specification, reference being had to the accompanying drawing, forming part thereof.

My design is illustrated in the accompanying drawing which shows the rein terret as viewed in perspective.

As shown, the rein terret comprises a horizontal bar 1 composed of two slightly curved branches 2 provided at their respective ends with vertically disposed oblong loops 3. At the middle of the bar where the two branches merge is a vertically disposed stem 4 from

the upper end of which diverging curved arms 5 branch, and the ends of these arms are connected by a bar 6. From one of the arms 5 a suitable distance below the bar 6 a finger 7 projects toward the other arm 5, but does not reach to the last mentioned arm, leaving a space 8 whereby an elongated or oblong shaped horizontally disposed loop 9 extending at right angles to the loops 3 is provided, and beneath this loop 9 is another loop 10 of substantially inverted cone-shape.

I claim:—

The ornamental design for a rein terret as shown and described.

ORRIN B. READ.
